UNITED STATES PATENT OFFICE

165,915

TWO SEATER COUCH FRAME

Lester Grundy, Glen Rock, N. J., assignor to Molla Incorporated, Westbury, N. Y., a corporation of New York

Application January 11, 1951, Serial No. 13,746

Term of patent 14 years

(Cl. D15—11)

To all whom it may concern:

Be it known that I, Lester Grundy, a citizen of the United States, now residing at Glen Rock, in the county of Bergen and State of New Jersey, have invented a new, original, and ornamental Design for a Two Seater Couch Frame, of which the following is a specification, reference being had to the accompanying drawing, forming part thereof.

The figure is a perspective view of a two seater couch frame, showing my new design.

I claim:

The ornamental design for a two seater couch frame, as shown.

LESTER GRUNDY.
